FIG. 3 is a right side elevation view thereof;

FIG. 4 is a left side elevation view thereof;

FIG. 5 is a top plan view thereof;

FIG. 6 is a front perspective view of a front sensor housing according to a second embodiment of our design;

FIG. 7 is a front elevation view thereof;

FIG. 8 is a right side elevation view thereof;

FIG. 9 is a left side elevation view thereof;

FIG. 10 is a top plan view thereof;

FIG. 11 is a front perspective view of a front sensor housing according to a third embodiment of our design;

FIG. 12 is a front elevation view thereof;

FIG. 13 is a right side elevation view thereof;

FIG. 14 is a left side elevation view thereof;

FIG. 15 is a top plan view thereof;

FIG. 16 is a front perspective view of a front sensor housing according to a fourth embodiment of our design;

FIG. 17 is a front elevation view thereof;

FIG. 18 is a right side elevation view thereof;

(Continued)

FIG. 19 is a left side elevation view thereof;
 FIG. 20 is a top plan view thereof;
 FIG. 21 is a front perspective view of a front sensor housing according to a fifth embodiment of our design;
 FIG. 22 is a front elevation view thereof;
 FIG. 23 is a right side elevation view thereof;
 FIG. 24 is a left side elevation view thereof; and,
